UNITED STATES PATENT OFFICE.

ALFRED HEALD, OF PHILADELPHIA, PA., ASSIGNOR TO HUGH McCALLUM,
ORLANDO CREASE, AND ANDREW J. SLOAN, OF SAME PLACE.

DESIGN FOR CARPETS.

SPECIFICATION forming part of Design No. 11,608, dated January 20, 1880.

Application filed December 22, 1879. Term of patent 3½ years.

To all whom it may concern:

Be it known that I, ALFRED HEALD, of Philadelphia, Pennsylvania, have produced or invented a new and original Design for a Carpet, (Case D²), of which the following is a specification.

My design for a carpet is fully shown in the accompanying photographic illustration.

The design comprises a profusion of geometrical figures of various configurations, arranged in respect to each other in a manner too clearly shown in the photograph to need particular description.

Some of the figures are ornamented with foliated designs, others with the conventional

scrolls and rosettes, and others with simple line-work.

Irrespective of the colors employed, I claim—

The design for a carpet, said design comprising the profusion of geometrical figures, arranged in respect to each other and ornamented substantially as described, and as shown in and by the accompanying illustration. 20

In testimony whereof I have signed my name to this specification in the presence of two subscribing witnesses. 25

ALFRED HEALD.
